UNITED STATES PATENT OFFICE.

EDDY T. MCKAIG, OF CHICAGO, ILLINOIS.

LUBRICATING APPARATUS FOR ENGINES.

SPECIFICATION forming part of Letters Patent No. 707,794, dated August 26, 1902.

Application filed December 9, 1901. Serial No. 85,184. (No model.)

To all whom it may concern:

Be it known that I, EDDY T. MCKAIG, a citizen of the United States, residing at Chicago, in the county of Cook and State of Illinois, 5 have invented certain new and useful Improvements in Lubricating Apparatus for Hydrocarbon-Engine Pistons, &c., of which the following is a specification.

My invention relates to certain new and useful improvements in lubricating apparatus, and I have shown the same as applied to the piston of a hydrocarbon-engine; and its purpose is to provide a simple and efficient device by which the piston shall be thoroughly 15 lubricated at all times without the possibility of failure.

Referring to the accompanying sheet of drawings, in which the same reference characters are used to designate identical parts 20 in all the figures, Figure 1 is a side elevation of a hydrocarbon-engine with my invention for lubricating the piston applied thereto, with a portion of the cylinder in section and broken away. Fig. 2 is a central section 25 through a portion of the cylinder, and Fig. 3 is a plan view of the top of the cylinder and piston.

In the drawings, *a* represents the frame of the engine; *b*, its piston; *c*, its cylinder; *d*, 30 the driving-shaft, having the customary crank connected by the piston-rod *e* to the piston *b*, and *f* is the fly-wheel on the shaft. The piston *b* is preferably provided with the customary metallic packing-rings and other suitable lubricating devices of that class com- 35 monly employed in machines of this class and not shown in the drawings. The cylinder *c* is furnished at its upper end with an external annular channel or groove *g*, which is prefer- 40 ably formed integral therewith. This groove *g* receives and holds the oil or other lubricant and is provided with a series of wicks *h*, ar- ranged, preferably, opposite each other, as shown in Figs. 2 and 3, and retained in the 45 annular oil-channel by means of an expansible spring-clip *j*, which is adapted to lie within the annular groove of the oil-chamber and hold the upper ends of the wicks in contact with the piston. The oil-channel is provided, 50 preferably, near the top of the cylinder *c*,

and the wicks are held in such position that they contact with the piston *b* when the latter reaches the upper end of its stroke.

The operation of the device will be readily apparent, as the wicks serve by capillary attraction to present to the cylinder a constant supply of oil, and a uniform lubrication is thus obtained without any other trouble than that of keeping the channel *g* filled with oil. As many wicks may be employed as are found necessary to secure the desired degree of lubrication, and the width of the wicks may be likewise arranged.

While I have shown my invention as applied to the lubrication of the piston of a gaso- 65 lene-engine, it will be readily perceived that it can be employed advantageously for lubricating other mechanisms, especially those in which a vertical plunger reciprocates in a cylinder.

While I have shown my invention as embodied in the form which I at present consider best adapted to carry out its purposes, it will be understood that it is capable of some modifications and that I do not desire to be 75 limited in the interpretation of the following claims except as may be necessitated by the state of the prior art.

What I claim as new, and desire to secure by Letters Patent of the United States, is— 80

1. In a device of the class described, the combination with the cylinder, of the piston adapted to reciprocate therein, a channel connected with the cylinder and adapted to receive a supply of the lubricant, and a wick 85 extending into said channel and having its other end in position to contact with the piston; substantially as described.

2. In a device of the class described, the combination with the cylinder, of the piston 90 adapted to reciprocate therein, a channel connected with the cylinder and adapted to receive a supply of the lubricant, a wick extending into said channel and having its other end in position to contact with the piston, 95 and means for holding said wick in said channel; substantially as described.

3. In a device of the class described, the combination with the cylinder, of the piston adapted to reciprocate therein, a channel con- 100

nected with the cylinder and adapted to receive a supply of the lubricant, a wick extending into said channel and having its other end in position to contact with the piston, and means for holding said wick in said channel consisting of the annular spring-clip *j*; substantially as described.

In testimony whereof I affix my signature in presence of two witnesses.

EDDY T. McKAIG.
